PAPER ROLL

Robert C. Moore, Long Island City, N. Y.

Application March 8, 1949, Serial No. 80,181

3 Claims. (Cl. 206—59)

1

This invention is a pencil of the general character disclosed in my prior Patents No. 1,266,299, of May 14, 1918, and No. 1,359,725, of November 23, 1920. Both of these prior pencils are provided with hollow magazines or housings adapted to contain a roll of paper, selected lengths of which may be withdrawn through a longitudinal slot in the magazine and torn off for memoranda purposes.

The present invention embodies many improvements upon the structures of said prior patents and for the first time provides a pencil of the character described which meets all practical requirements.

Speaking generally, the pencil of the present invention has a body provided with a writing point at one end. Upon the other end of the body of the pencil is mounted a hollow tube with a longitudinal slit and into the opposite end of the tube is fitted a manually rotatable finger piece. A roll of paper of novel construction is positioned within the tube with one end of the roll making its own bearing within the tube and the other end of the roll tightly fitted into a socket in the inner end of the finger piece, whereby rotation of the finger piece will cause a strip of the paper to be torn from the roll along longitudinal score lines and fed through the slot in the tube. The exterior of the finger piece is circumferentially toothed to form an annular ratchet and on the exterior of the tube a spring pawl is mounted to engage with such ratchet to limit rotation of the finger piece to a direction which will feed the paper through a slot in the tube. The pawl is preferably formed integral with a clip generally used on fountain pens, magazine pencils and the like.

An important novel feature of the invention resides in the roll of paper to be dispensed. Long experience with the dispensing of paper from pencils of this kind has demonstrated that the feed of the paper from a rotatable reel through a slot cannot be satisfactorily and efficiently performed. I have discovered, however, that, if the paper is formed into and maintained in a tight roll and is scored or otherwise provided with lines of weakness which converge as the scored portions approach the center of the roll, a clean tear of the paper from the roll will result. I find it convenient to glue to one another the successive convolutions of the roll at the opposite ends of the roll. This insures permanent end portions on the ends of the roll, while permitting those portions of the roll between the lines of weakness to be readily torn free from the remainder of the

roll along these lines. When a roll thus constituted is housed within a slotted tube as specified, successive portions of the paper may be torn free from the roll between said lines and projected through a slot in the tube, to be torn free along the edge of said slot as desired. When the roll is so constituted, the tearing away of a portion of the paper exterior of the tube will leave the remaining torn edge of the paper positioned

10 at the outlet of the slot for those portions of the paper between these lines of weakness will remain tightly rolled and will not tend to unroll or loosen from the remainder of the roll. The making of a roll in this manner and the resulting roll constitute an important feature of this invention.

Another feature of this invention consists in the simplicity of the construction, its economy in paper and its ease of manipulation.

20 Features of the invention, other than those adverted to, will be apparent from the herein-after detailed description and appended claims, when read in conjunction with the accompanying drawing.

25 The accompanying drawing illustrates one practical embodiment of the invention, but the construction therein shown is to be understood as illustrative only, and not as defining the limits of the invention.

30 Figure 1 is a central longitudinal section through a pencil embodying the present invention with certain portions of the structure in elevation in the interest of clearness.

Figure 2 shows the manner of scoring the paper in the formation of the roll.

35 Figure 3 is a section on the line 3—3 of Figure 1.

Figure 4 is a section on the line 4—4 of Figure 1.

Figure 5 is an elevation of the upper portion of Figure 1 looking from the left hand side thereof.

40 Figure 6 shows those portions of the paper roll remaining after all dispensable portions of the paper of such roll have been withdrawn therefrom.

45 By reference first to Figure 2, 1 designates an elongated web of paper and the dotted lines 2 indicate lines of weakness, such as may be produced by scoring, perforation or otherwise. These lines of weakness 2 converge in the direction from which the dispensing takes place when

50 the web 1 is wrapped into a roll 3, as indicated at the top of Figure 2. In other words, the paper web is scored along the diverging lines 2 and rolled, as indicated at 3, until all of the web has been formed into the roll. When this has been

accomplished, an adhesive is applied to the opposite ends of the roll as at 4 and 5 to bind the successive convolutions of the web firmly in place so that the roll cannot unroll or loosen. The application of adhesive may be by a sponge or otherwise, momentarily pressed against the ends of the roll or the ends of the roll may be dipped in an adhesive. This is optional. However, when the roll is formed, the paper at its opposite ends will be adhesively secured so as to maintain the web in rolled condition. The adhesive should not, however, extend beyond the score lines 2, between which the paper strip 1a is adapted to be removed by tearing or severing along such lines.

In forming the paper roll, I preferably wrap the web about a suitable core 6, shown in Figures 6 and 4. This core may be and preferably is in the form of a hollow tube, rod or dowel of small diameter which serves the purpose of conventionally starting the roll and also serves to space the opposite end portions 1b-1c of the roll apart when the greater portion of the paper has been torn therefrom and until the roll is exhausted. Although the spacing of the score lines 2 from the opposite ends of the roll may be the same from both edges of the paper web, I preferably make the spacing at one side of the web greater than at the other side in the interest of economy, the larger spacing being sufficient to afford a firm anchorage between the roll and the dispensing plug as presently explained.

The roll 3 is adapted to be housed within a tube 7 of metal, plastic or any other suitable material, one end of which is adapted to snugly fit a reduced portion 8 on the rear end of the pencil body 9. The engagement of this end of the tube with the portion 8 firmly secures these parts together in a detachable manner although they may be adhesively or otherwise secured together if desired. The upper end of the tube is adapted to rotatably receive the reduced portion 10 of a rotatable finger piece 11, provided interiorly with a cavity 12 into which one end portion 1c of the paper roll 3 may be received with a snug fit.

The exterior of the finger piece 11 is circumferentially toothed, as indicated at 13, to form an annular ratchet and with this ratchet is adapted to cooperate a spring finger 14 formed upon a pawl spring 15, as shown best in Figures 1 and 5. This pawl spring may form a continuation of a pocket clip 16, as shown, or may be made separate therefrom if desired. The clip and ratchet spring are held in place upon the tube by rivets 17 or otherwise. The purpose of the ratchet is to limit rotation of the finger piece to that direction appropriate to unwind the dispensable portion, i. e., the strip 1a, of the paper web from the roll and project it through a longitudinal slot 18 in the side of the tube. This slot is preferably cut at an angle as shown in Figure 4.

The paper roll is adapted to be introduced into the tube by withdrawing the finger piece 11 from the upper end of the latter. Before placing the roll in the tube a small portion of the strip 1a, between the lines 2, should be torn from the roll to provide it with a loose wing extending therefrom. One end portion 1c of the roll is then pressed into the socket 12 of the finger piece and the roll and finger piece are then inserted into the upper end of the tube until the reduced portion 10 of the finger piece comes to a seat within the tube.

If the finger piece is thereafter turned in the direction permitted by the ratchet, the free end

of the wing on the paper will engage with and enter the slot 18 and be projected therethrough and, if rotation of the plug is continued, more and more of the paper strip will be torn from the roll and projected through the slot. Alternatively, that portion of the paper strip which is projecting through the slot, may be grasped and withdrawn therethrough. This operation will contemporaneously cause consecutive portions of the strip 1a to be torn along the scored lines 2, so that it may be dispensed through the slot 18.

When a sufficient amount of paper has been withdrawn for particular memorandum in mind, the thus dispensed length of the paper may be torn off from the remainder of the roll at the edge of the slot 18, which is preferably sufficiently sharp or rough to form a satisfactory tearing edge. After this dispensed part is torn away, that portion of the roll within the tube is held stationary by the ratchet and pawl, with the free end of the strip in the slot 18, so that a further portion of the paper may be dispensed as and when desired.

When all of the paper strip 1a of the roll, between the lines 2, has been dispensed, the roll appears as in Figure 6. The central portion of the core 6 is visible, with the two opposite end portions 1b and 1c or the roll beyond the score lines still in place on the core. The advantage of this is that these two opposite end portions serve to guide the roll while all of the paper is dispensed therefrom, for the lower end portion 1b maintains a full size bearing with the interior of the tube while the upper end portion 1c maintains a full size tight contact with the socket 10. To apply a new and unused roll, the finger piece 11 is simply withdrawn, carrying with it the remainder of the paper roll shown in Figure 6 and this used roll is removed from the socket 10 and a new one inserted in its place and re-assembled on the pencil.

I wish to lay particular stress upon the convergence of the line of weakness 3. This feature is of great importance to the present invention for it allows the paper to tear cleanly from the roll and experience has demonstrated beyond question that this cannot be accomplished if the score lines 2 were parallel. By the converging arrangement shown, the paper is free to tear cleanly along the scored lines and does not have to tear in contact with or over edges previously torn. The paper will thus remain tight on the roll and the strip 1a will readily be severed along the lines of weakness and projected through the slot in the tube, leaving the tab end of such strip in juxtaposition with the slot in the tube and in a position to be projected therethrough by the next dispensing operation. If parallel lines of scoring were used, it has been conclusively demonstrated that the dispensing force projecting paper through the slot will break the parallel scoring of the paper roll within the slot for a considerable portion of the web of the roll, causing a considerable length of loose paper to remain within the tube, thereby making it practically impossible to dispense any additional paper through the slot of the tube.

The foregoing detailed description sets forth the invention in its preferred practical form, but the invention is to be understood as fully commensurate with the appended claims.

The part 9 shown in the accompanying drawings has been specifically referred to as a pencil. It may be of the usual type embodying a sliver of graphite or may be of the magazine type, or, if

desired, it may be a pen of conventional or ball point type, without departing from this invention.

Having thus fully described the invention, what I claim as new and desire to secure by Letters Patent is:

1. As a new article of manufacture, a web of paper having converging lines of weakness extending longitudinally thereof in spaced relation from the lateral edges of the web and from each other, said web of paper being rolled into a compact roll with the lines of weakness at their maximum spacing at the outer terminus of the web.

2. As a new article of manufacture, a web of paper having converging lines of weakness extending longitudinally thereof in spaced relation from the lateral edges of the web and from each other, said web of paper being rolled into a compact roll with the lines of weakness at their maximum spacing at the outer terminus of the web, and adhesive applied to the successive convolutions of the paper at the opposite ends of the roll to maintain those portions of the web between the lines of weakness and said opposite ends of the roll in permanently rolled condition while permitting severance along the lines of weakness of

the intermediate portion of said web which lies between said lines of weakness.

3. As a new article of manufacture, a web of paper having converging lines of weakness extending longitudinally thereof in spaced relation from the lateral edges of the web and from each other, said web of paper being rolled into a compact roll with the lines of weakness at their maximum spacing at the outer terminus of the web, and an adhesive applied to the opposite ends of the roll and spaced from said lines of weakness.
